HAND-OILER

Jesse M. Holden, Gardena, Calif.

Application November 30, 1936, Serial No. 113,353

5 Claims. (Cl. 221—51)

This invention relates to improvements in a hand oiler of the type having a reservoir with a thumb-operated, flexible, spring bottom; and the objects of my invention are, first, to provide a pump to be contained entirely within the reservoir of the oiler and operable by thumb pressure and the consequent inward flexing of the spring bottom; second, to provide a pressure pump oiler which will dispense oil with the spout directed in practically all positions, especially with the spout pointing above the horizontal, whereby oiling of difficult or impossible points may be easily accomplished; third, to provide a pump mechanism readily adaptable to be fitted to various sizes of reservoirs and to different lengths of spouts; fourth, to provide means for venting air into the oil reservoir as oil may be pumped out, the venting means also serving to prevent the forcing out of the spout of oil by reason of the expansion of the air within the reservoir due to a rise in the ambient temperature.

I attain these objects by means of the mechanism illustrated in the accompanying drawing, in which Fig. 1 is a sectional elevation of an oiler with a pump mechanism fitted therein; Fig. 2 is a broken-away view of an oiler held with the spout directed on a line below the horizontal and with the visible portion of the pump mechanism in elevation; and Fig. 3 is a sectional view of an oiler spout, broken away at a point above its connection with its reservoir and intended to illustrate an optional method of conducting the oil discharge to the nozzle and of venting air to the reservoir.

Referring to the drawing by numbers of reference, 10 designates a can body which constitutes a reservoir for oil or other liquid contents and 11 designates the flexible spring bottom of the body. Said body is provided at its upper part with a mouth 12, of substantially, cylindrical shape, threaded internally, and with an outwardly flanged portion 12' at its upper extremity. Said mouth may be a separate part, spun onto or otherwise attached to the body, or it may be integral therewith and spun or formed to the shape substantially as shown. A closure 13 is in the form of a hollow cylindrical piece, externally threaded at its lower end to screw into the internally threaded can mouth 12, and is provided with an outwardly flanged portion 13' formed at its upper end, which flange is knurled on its periphery to provide a non-slip grip for the fingers. The flange 13' of the closure 13, co-operates with the flange 12', of the can mouth 12, to receive between their opposed faces a substantially circu-

lar ring gasket 14, of soft or non-metallic material for sealing the closure against leakage.

The hollow part of the closure 13 is provided with an inwardly projecting, apertured flange 13" formed at its upper end and adapted to receive a spout 16. Said spout is of a conventional, tapering cylindrical form, being of smaller diameter at its discharge nozzle than at its point of attachment to the closure, and has a flange 16', formed at its larger end, designed to be held against the flange 13" of the closure 13. Said closure is also threaded internally from its lower end to receive an externally threaded pump body 18 which, when screwed into place, bears with its upper face against the spout flange 16' to hold the spout 16 firmly in place. A gasket may be placed between flanges 16' and 13" to insure tightness at this joint.

The pump body 18 incorporates a pump cylinder 19 comprising a length of cylindrical tubing 20 pressed forcibly into an annular groove formed in the lower part of said body which receives, within its open lower end, a telescopically associated, closely fitting piston 20, of hollow cylindrical section having a closed lower end. A helical compression spring 21, contained within the hollow piston and cylinder and having its opposite ends bearing against the pump body and the closed end of the piston, respectively, serves to force the piston downward to bear against the can bottom 11. Said spring is formed with a few turns at both ends of the spring of larger diameter than the body portion thereof and thereby adhering to the walls of said piston and cylinder by friction therewith; and the length of said spring is made such that, when the closure and pump assembly is removed from the reservoir and the spring may fully extend, said spring will not extend sufficiently to force said piston out of the bore of said cylinder but will retain the piston therein by 35 frictional grip upon the co-operating parts.

A discharge passageway 22, concentrically located within the pump body 18, leads upward from the interior of the cylinder 19 to an enlarged continuation 22' thereof, where said enlargement 45 forms a chamber for the retention of a check-ball 23, which seats against a shoulder 22" formed by said enlargement. A straight cylindrical tube 24 provides a continuation of the discharge passage 22, being pressed into the enlargement 22' 50 thereof, and has an internal diameter less than the diameter of said check-ball and restricts the ball to a limited travel within the chamber. Notches 24 are cut transversely at the lower end of tube 24 to provide passage for liquid into said 55

tube when the ball is carried upward against the end of the tube by liquid discharged from the cylinder 19.

The tube 24 is, furthermore, of such diameter and length its upper end will fit closely within the interior of spout 16 at a point near the end of the straight portion of said spout when the pump body 18 and closure 13 are assembled. A small vent hole 25 is drilled through the wall of tube 24 near its discharge end and a small vent passage 30, through the body 18, provides communication from the annular space between tube 24 and spout 16 into the reservoir of the oiler. Air may thereby find passage into or out of the reservoir through the previously mentioned passage 30, the annular space between tube 24 and spout 16, the vent hole 25 and the nozzle of spout 16.

A chamber 26, drilled into the pump body 18 from the lower end, accommodates a suction check-ball 28; and a suction tube 27, bent as illustrated, is pressed into chamber 26, the end of said tube within the chamber being bevelled as a seat for said check-ball. A passageway 29 communicates between passageway 22 and chamber 26 to provide for the entrance of liquid from the suction tube 27 into the pump cylinder 19.

The spout 16 is assembled with the pump body 18 so that the bent nozzle of the spout will be pointed in the same direction as the suction tube 27 so that, when the oiler is held with the spout inclined below the horizontal and the nozzle pointed downward, the suction end of tube 27 will be immersed in the liquid contained within the reservoir, as illustrated in Fig. 2.

Either or both of the check-balls 23 and 28 may be provided with springs for positively seating the balls on their respective seats, but I prefer to depend on the reversal of liquid flow, when the pump is operated, to carry the balls to their seats.

The operation in dispensing oil is as follows. The reservoir containing sufficient liquid to immerse the suction entrance of tube 27, upon inward flexing of the can bottom 11 by pressure of the thumb or fingers, the piston 20, being in contact with the inner side of the can bottom, is carried upward therewith and compresses spring 21 and, the suction check-ball 28 seating and preventing the return of liquid through the suction tube, liquid is forced out of the cylinder by way of passage 22, around the discharge check-ball 23, through discharge tube 24 and through nozzle of spout 16. Upon release of pressure on the can bottom, its resilience and the force of spring 21, acting through the piston 20, causes it to return to the original convex form illustrated in Fig. 1. The downward stroke of the piston 20 causes an initial return flow of liquid from the spout which carries the discharge check-ball to its seat 22", the suction check-ball 28 is lifted and liquid flows by way of suction tube 27, chamber 26 and passageways 29 and 22 to refill the cylinder 19.

It may be seen that the end of the suction tube 27 will be immersed in the liquid of the reservoir, when the oiler is held in the hand and operated for dispensing, with the spout in practically all positions from vertically upward to nearly vertically downward and that, even in the vertically downward position, advantage is had of the capacity of the cylinder which may be emptied by dispensing operation.

In order to dispense liquid from the oiler it is necessary to provide means for the entrance of air to replace the volume of liquid dispensed. Be-

fore air can enter the reservoir through the vent passages provided in my invention, and previously described, any liquid standing in the space between the nozzle of spout 16 and the vent hole 25 of tube 24 must first be drawn back into the reservoir by way of the vent holes 25 and 30; and this comprises a valuable feature of my invention. By this feature of draining the spout nozzle, dribbling of liquid from the nozzle after using the oiler is prevented and breathing action from expansion of air in the reservoir cannot force liquid from the reservoir out of the spout.

In this connection, reference may be had to Fig. 3 which illustrates another method of conducting liquid from the pump to the spout nozzle and of venting to the reservoir. This figure, representing an oiler spout broken away above its point of attachment to a reservoir, is assumed to have similar pump dispensing mechanism as illustrated in Fig. 1. In Fig. 3 the discharge tube 24a is extended to project slightly beyond the nozzle 16b, of spout 16a, and is a loose fit at the point of least diameter of said nozzle, providing an annular space for passage of air at said point designated 31. Air venting to or from the reservoir would follow a similar course as in the arrangement shown in Fig. 1, namely, through the annulus 31, the space between tube 24a and spout 16a and the vent passage 30.

The mechanism is readily adaptable to different sizes of reservoirs by altering the lengths of cylinder 19, the piston 20 and spring 21; and to different lengths of spouts by altering the length of tube 24.

It is understood that the construction of the invention is not to be limited to the actual detail shown and that it may be modified within the scope of the claims following without departing from the spirit and scope of the invention.

Having thus described and illustrated my invention, what I claim and desire to secure by Letters Patent is:

1. In a hand oiler having a body, a flexible spring bottom, a reduced mouth for said body, a closure for said mouth and a spout attached thereto; a pump mechanism attached to said closure, operable by inward flexure of said bottom and comprising a body containing a suction and a discharge valve, a suction tube from said body extending to the lower part of the reservoir of said oiler body, a cylinder and slideable piston and means for forcing said piston outward against said flexible bottom.

2. In a hand oiler having a body, a flexible spring bottom and a mouth and closure therefor, said closure incorporating a spout and a pump mechanism integral therewith; a discharge tube for said pump mechanism extending upward within said spout to a point near the nozzle thereof.

3. In a hand oiler having a body, a flexible spring bottom and a mouth and closure therefor, said closure incorporating a spout and a pump mechanism integral therewith and a discharge tube for said pump mechanism extending upward within said spout to a point near the nozzle thereof; means for venting air to the reservoir of said body comprising a vent hole through the wall of the discharge tube adjacent the discharge end and supplementary passageways into said reservoir.

4. In a hand oiler having a body, a flexible spring bottom, a mouth and a closure therefor, said closure incorporating a spout and pump mechanism integral therewith and a discharge

5 tube for said pump mechanism extending upward within said spout to or beyond the nozzle thereof and means for venting air to the reservoir of said body, comprising an air passage between said tube and said spout at said nozzle and supplementary passageways into said reservoir.

10 5. In a hand oiler having a body, a flexible spring bottom, a reduced mouth for said body, a closure for said mouth and a spout attached thereto, a pump mechanism attached to said closure, operable by inward flexure of said bottom

and comprising a body incorporating a suction and a discharge valve and a cylinder integral therewith accommodating a hollow piston with a closed outer end; a spring contained within said piston and cylinder, the end turns of said spring being formed of greater diameter than the central portion thereof and forcibly gripping the interior walls of said piston and cylinder respectively.
